(57) **CLAIM**

The ornamental design for a combined container and insert, as shown and described.

DESCRIPTION

FIG. 1 is a perspective view of a combined container and insert showing our new design;

FIG. 2 is a perspective view of the design shown in FIG. 1 in partial assembly;

FIG. 3 is a perspective view of the design shown in FIG. 1 in partial assembly;

FIG. 4 is a perspective view of the design shown in FIG. 1 in partial assembly;

FIG. 5 is a perspective view of the design shown in FIG. 1 in complete assembly;

FIG. 6 is a front view of the design shown in FIG. 5;

FIG. 7 is a rear view of the design shown in FIG. 5;

FIG. 8 is a left side view of the design shown in FIG. 5;

FIG. 9 is a right side view of the design shown in FIG. 5;

FIG. 10 is a top view of the design shown in FIG. 5;

FIG. 11 is a bottom view of the design shown in FIG. 5;

FIG. 12 is a perspective view of the combined container and insert shown in FIG. 1, showing a component insert removed from the combined container and insert for clarity of disclosure;

FIG. 13 is a front view of the design shown in FIG. 12;

FIG. 14 is a rear view of the design shown in FIG. 12;

FIG. 15 is a left side view of the design shown in FIG. 12;

FIG. 16 is a right side view of the design shown in FIG. 12;

FIG. 17 is a top view of the design shown in FIG. 12;

FIG. 18 is a bottom view of the design shown in FIG. 12;

FIG. 19 is a perspective view of the combined container and insert of FIG. 1, showing a component insert removed from the combined container and insert for clarity of disclosure;

FIG. 20 is a front view of the design shown in FIG. 19;

FIG. 21 is a rear view of the design shown in FIG. 19;

FIG. 22 is a left side view of the design shown in FIG. 19;

FIG. 23 is a right side view of the design shown in FIG. 19;

FIG. 24 is a top view of the design shown in FIG. 19;
FIG. 25 is a bottom view of the design shown in FIG. 19;
FIG. 26 is a perspective view of the combined container and insert of FIG. 1, showing a component insert removed from the combined container and insert for clarity of disclosure;
FIG. 27 is a front view of the design shown in FIG. 26;
FIG. 28 is a rear view of the design shown in FIG. 26;
FIG. 29 is a left side view of the design shown in FIG. 26;
FIG. 30 is a right side view of the design shown in FIG. 26;
FIG. 31 is a top view of the design shown in FIG. 26;
FIG. 32 is a bottom view of the design shown in FIG. 26;
FIG. 33 is a perspective view of the combined container and insert of FIG. 1, showing a component insert removed from the combined container and insert for clarity of disclosure;

FIG. 34 is a front view of the design shown in FIG. 33;
FIG. 35 is a rear view of the design shown in FIG. 33;
FIG. 36 is a left side view of the design shown in FIG. 33;
FIG. 37 is a right side view of the design shown in FIG. 33;
FIG. 38 is a top view of the design shown in FIG. 33; and,
FIG. 39 is a bottom view of the design shown in FIG. 33.
The broken lines which define the bounds of the claimed design in FIGS. 19-39 form no part thereof. The broken line showing of a surface design in FIGS. 1-6 and 8-11 is for the purpose of illustrating environmental structure and forms no part of the claimed design.
